UNITED STATES PATENT OFFICE.

FREDERICK W. LAENCHER, OF BROOKLYN, NEW YORK, ASSIGNOR TO A. KIMBALL COMPANY, OF NEW YORK, N. Y., A CORPORATION OF NEW YORK.

MACHINE FOR ASSEMBLING MARKING TAGS IN SUPERIMPOSED RELATION.

Application filed January 18, 1923. Serial No. 618,503.

To all whom it may concern:

Be it known that I, FREDERICK W. LAENCHER, a citizen of the United States, and resident of Brooklyn, county of Kings, State 5 of New York, have invented an Improvement in Machines for Assembling Marking Tags in Superimposed Relation, of which the following description, in connection with the accompanying drawing, is a specification, like characters on the drawing representing like parts.

This invention relates to improvements in machines for assembling marking tickets in superimposed relation and the object 15 thereof is to provide means for piling the tags, one upon the other, with the edge of each superimposed tag lying beyond the edge of the tag next beneath it.

Usual marking tags, such as, pin tickets, 20 string tags, etc., consist of a card or ticket having attaching means extending from the under face of the card. In the usual manufacture of such marking tags a continuous strip of ticket material is passed through a 25 machine which secures the attaching device to the strip at intervals so that when the strip is cut midway between the attaching devices the completed marking tags are formed. It is usual also to provide an extension of the 30 table or guide for the strip beyond the mechanism which applies the attaching device and to print suitable designations upon the tags before they are cut from the strip. In usual machines the tags which are thus 35 cut from the strip drop into a receptacle from which they are removed, counted and placed in suitable packages. In usual machines of this character a cutter is employed at the end of the guide for the strip which 40 comprises an upwardly reciprocating blade which is operated intermittently in synchronism with the strip feeding mechanism to sever the tags and drop them into the receptacle. In the operation of such machines 45 the resilience of the ticket material causes the tags to flip over so that they drop miscellaneous into the receptacle.

One of the objects of the present invention is to provide a novel form of cutting 50 mechanism which will sever the tags successively from the strip and permit them

to drop in substantially horizontal position so that each tag will be superimposed upon the one next beneath it.

A further object of the invention is to 55 provide means for depositing tags having attaching devices extending from one face thereof in such a manner that the attaching device of each superimposed tag overlies and preferably engages the edge of the next 60 tag beneath it so that the tags may be compactly assembled and packaged in a relatively small container.

A further object of the invention is to 65 provide a machine of the character described with a chute to receive the tags as they are cut from the strip and provided with means, such as, a pusher which operates to shove each tag along the chute a short distance so that the next tag cut off 70 will fall upon it with the attaching device projecting behind it so that as the operation proceeds the tags lying on top of each other will be feathered out as they ride down the chute and enable the operator to 75 count off a predetermined number of tickets, lift them from the bottom of the chute and deposit them in a suitable packing box in a closely arranged superimposed position.

Other objects and features of the invention will more fully appear from the following description and the accompanying drawings will be particularly pointed out in the claims.

The drawings illustrate a preferred embodiment of the invention as applied to the usual form of tag making machine.

In the drawings:

Fig. 1 is a front elevation of the invention as viewed from the delivery end of the tag making machine to which it is applied;

Fig. 2 is a plan view of the same showing a portion of the frame and the table or guide of the tag making machine with the 95 present invention applied thereto; and,

Fig. 3 is a vertical longitudinal sectional view on line 3-3 Fig. 1, viewed from the right toward the left.

Only such mechanism is illustrated in the 100 accompanying drawings as is necessary to show the means for severing the tags from a

continuous strip and depositing the same in superimposed relation, this mechanism being adapted to be associated with a usual form of tag making machine such, for example, as is illustrated in Patent No. 457,782 granted to A. Kimball, August 18, 1891, for machines for making pin tickets. In this machine a continuous strip of ticket or tag material is fed intermittently to mechanism which inserts an attaching device, specifically a staple, through the ticket adjacent one edge and bends the looped portion of the staple around and beneath the edge of the ticket. Further intermittent feeding of the pin ticket strip passes the strip between a pair of cutters which sever tickets or tags of uniform width from the strip and drop the same into the receptacle. Machines of this type are also provided with printing mechanisms as above described.

The mechanism illustrated in the accompanying drawings is designed to be secured to the end of the table or guide for the marking tag strip in place of the cutting mechanism previously employed.

As illustrated herein the cutting and severing mechanism is mounted upon the bed 1 of the pin ticket making machine which has the usual legs 2 and 3 extending downwardly and preferably integral with the bed. The edges of the bed are provided with inwardly extending dove-tail grooves 4 and 5 which receive complementary dove-tail guides 6 and 7 extending downwardly and preferably integral with a carriage 8 which supports the cutting and assembling mechanism. A suitable gib 9 may be introduced between the dove-tail members 5 and 7 to assist in assembling the machine.

The carriage 8 comprises vertical webs 10 and an integral table 12 provided with a longitudinal groove 13 to receive the shanks of the pins or staples 14 which extend downwardly from the pin tickets or tags 15 which, as they approach the cutting mechanism, are in the form of a strip. By means of the dove-tail connection between the carriage for the cutting and assembling mechanism and the bed of the machine the cutting mechanism may be adjusted longitudinally with relation to the bed of the machine in such a manner as to permit the cutting mechanism to be set to accord with the print and feed motion for cutting tickets of different sizes, suitable means (not shown) being provided for securing the carriage in the proper adjusted position. When the carriage is assembled upon the pin ticket machine the table 12 forms a continuation of the table of the pin ticket machine so that the tickets are fed directly from the stapling and printing mechanism to the cutting mechanism.

The carriage 8 is provided at its end with a vertical standard comprising uprights 16 and 17 connected at their upper ends by

a transverse, preferably integral member 18 and also connected at a short distance above the table by a transverse bridge member 19. The face of this standard is flush with the end of the carriage and desirably is planed to provide a guiding base for the reciprocating cutter mechanism. Guides 20, having respectively inclined or beveled guiding faces 21, are secured to the face of the standard adjacent its ends by suitable screws 75 or bolts 22.

The cutter frame comprises a pair of vertical guiding members 23 having inclined or beveled faces 24 engaging the faces 21 of the guides 23, a horizontal central connecting member or web 25 and a bottom connecting base member 26, all of which may be formed as an integral construction. The lower cutting blade 27 is secured to the base member of the cutting frame by suitable screws 28. The co-operating upper cutting blade 29 is connected by suitable screws 30 to a transverse plate 31 which in turn is connected to the guides 20 by screws 32.

The edge of the upper knife 29 is located in a plane sufficiently above the plane of the table 12 to enable the strip of tag material to be fed beneath it and a stripper is provided which engages the upper face of the advancing tag strip and guides it beneath the edge of the upper stationary cutter blade and also acts as a yieldable stripper to strip tags from the upper knife after the cutting operation. This stripper comprises a plate 33 which preferably extends over the end portion of the table 12 and is preferably provided with a thickened and downwardly beveled portion adjacent the stationary blade 29 and also is provided with a plurality of guide rods or stems 34 which extend upwardly through suitable apertures or ways in the plate 31 and are provided at their upper ends with nuts 35 which are engaged by helical springs 36 located within tubular members 37 which are suitably secured at their lower ends by tubular nuts 38 to the upper edge of the plate 31. The springs 36 act normally to force the stripper downwardly to a position a short distance above the plane of the advancing strip of tag material, the thickened end portion extending to the plane of the edge of the upper cutter so as to direct the tag material beneath said upper cutter.

Any suitable means may be provided for reciprocating the cutting frame. As illustrated in Fig. 1 the lower transverse member 26 of the cutting frame is provided with a downwardly extending arm 39 provided with a boss 40 to which the bifurcated upper end 41 of an actuating link or arm 42 is connected by a suitable pivotal bolt 43, the arm or link 42 being actuated in synchronism with the feeding mechanism of the printing machine by a suitable mechanism 130

not shown, but which may be similar to that disclosed in the patent to Kimball above identified.

In usual tag making machines the tickets are severed by a reciprocating cutter having a lower movable blade and when the strip is severed by the upward movement of such a cutter the material is sufficiently distorted or flexed to flip the ticket over so that successive tickets drop into a receptacle beneath the cutter in a miscellaneous order. The cutting mechanism of the present invention differs from the old cutting mechanism in that a stripper is provided which 10 operates with the lower reciprocating cutter and prevents flexure on the ticket material and, consequently, enables the cut-off ticket to drop without being flipped over or otherwise displaced, so that a series of marking 15 tags or tickets can be cut from the strip and dropped in proper superimposed relation.

A further object of the invention is to provide means for assembling in continuous 20 superimposed relation, as they are cut from the strip, a series of marking tags having attaching devices projecting from the face or end of the tag. Obviously such tags cannot be superimposed directly upon each 25 other and the present invention contemplates the provision of mechanism which will advance the marking tags as they are successively cut from the strip in such a manner that the attaching members of each superimposed tag will extend beyond the end 30 of the tag next beneath it.

A further object of the invention is to provide a suitable chute to receive the marking tags thus severed from the strip 35 and superimposed so that the tags may be delivered from the chute in a continuous superimposed overlapping relation which will enable the operator to remove a suitable number of tags from the chute while still in superimposed relation and deposit the same in suitable packages, thereby enabling a larger number of tags to be packaged in a box than is usual, without the necessity of rearranging the tags, and also enabling the 40 package to be so formed as to permit the tags to be readily taken out one by one as they are to be applied without the pins being touched by the fingers of the operator.

In the preferred embodiment of the invention illustrated herein the means for supporting the tags, as they are delivered from the cutting mechanism, comprises a chute 45 preferably formed in two parallel sections which are suitably inclined and curved to enable the superimposed tags to be readily forced down the chute by the assembling mechanism.

As illustrated in the accompanying drawings the chute comprises a pair of relatively 50 adjustable guiding members or rails 44 and

45 which are supported upon suitable brackets secured to the carriage of the cutting mechanism. In the preferred construction an L-shaped bracket 46 is secured by a bolt 47 to the standard 16 and a second 50 bracket 48 is secured to the arm 49 of the bracket 46 by a bolt 50. The bracket 48 is provided with a recess which receives the curved upper end of the member 44 of the chute. The bracket 48 is also provided with 55 an extension 51 having a slot 52 along which the other chute member 45 may be held in adjusted position by a bolt 53. To support the other end portion of the chute an L-shaped bracket 54 is secured to the vertical 60 standard 17 of the carriage by a bolt 55 and to the arm 56 of said bracket a vertical member 57 of another bracket is secured having a horizontal slotted arm 58 provided with a guide-way 59 in which a carriage 60, connected to the member 45 of the chute is connected, and which may be adjustably positioned in said guide-way by a suitable bolt 61. The chute sections 44 and 45 are each provided with upwardly extending flanges 65 to engage the edges of the marking tags.

By reason of this adjustable construction the section 45 of the chute may be positioned properly with relation to the section 44 to 70 guide tags of different widths.

It will be noted that the section 44 of the chute lies directly beneath the stationary cutter blade 29 and that the flange of said chute is omitted from the portion of the 75 chute which extends beneath the cutter.

In the operation of the machine the successive marking tags cut from the strip drop directly upon the chute and as they pile up slide gradually down the chute in superimposed overlapping relation.

Where marking tags are provided with attaching devices, such as, pins or staples, it is desirable that the tags shall be successively advanced positively along the chute so that the end of each superimposed tag, which carries the attaching device, shall overlap the tag next beneath it. This is accomplished by providing a pusher which engages the dropping tag and moves it lengthwise relatively to the chute as it falls 100 from the cutter upon a previously dropped tag.

In the preferred construction illustrated herein a rotary pusher is provided comprising a series of preferably curved arms 62 which extend from a hub 63 which is rotatably mounted upon a stud 64 projecting from the member 44 of the chute. The hub 63 is also provided with a ratchet 65 which is operated intermittently by a suitable pawl and is restrained from backward movement by suitable detent.

In the preferred construction illustrated an actuating pawl 66 is pivotally mounted upon a stud 67 upon a plate or lever 68

which is pivotally mounted upon the stud 64, the pawl being forced into engagement with the ratchet teeth of the hub by a spring 69. The plate or lever 68 is provided with a laterally extending stud 70 which is pivotally connected by a link 71 to an arm 72 which is pivotally mounted on a stud 73 extending from a plate 74 which is connected to the reciprocating cutter frame 26. The link 71 is adjustably connected to the arm 72 in order that the pusher arms 62 may be positioned with respect to the reciprocation of the cutter in such a manner as properly to engage and advance the tags.

In the present construction the rod 71 is shown as screw threaded and is adjustably secured to the arm by nuts 76 and 77 engaging opposite sides of the arm 72.

20 Retrograde movement of the rotatable pusher is prevented by a detent pawl 78 which is pivotally mounted upon a stud 79 upon a bracket 80 fixedly secured upon the stud 64, the detent being held in engagement with the ratchet by helical springs 81 as shown more clearly in Fig. 2.

In the operation of the device the marking tag strip with the staples or other attaching devices secured thereto are advanced intermittently by the feeding mechanism of the printing machine to the cutters, each tag being projected beyond the edge of the stationary cutter 29. The lower movable cutter is then reciprocated upwardly, first 30 engaging the tag, and then raising the edge of the same, together with the stripper, sufficiently to sever the tag by co-operation with the stationary cutter. After the tag is severed it is engaged by one of the rotating pusher arms 62 and forced lengthwise of the chute so that after one tag has been dropped into the chute the next tag is deposited upon it with the attaching device 35 lying back of and preferably engaging the edge of the tag next beneath. As the tags are thus successively deposited the action of the pusher gradually forces the same down the chute with the tags stacked in superimposed relation as illustrated in Fig. 1. 40 As the tags progress down the chute they are removed in suitable numbers by the operator and transferred to a packing carton.

By reason of the adjustability of the carriage for the cutter and assembling mechanism, and also by reason of the adjustability of the width of the chute, the device can be arranged properly to cut and assemble tags of different widths.

60 It will be obvious that the invention may be employed for the purpose of assembling tags having other kinds of attaching devices, such as, strings, or having attaching pins projecting in other angular relations to the faces of the tags than those herein illustrated.

It will also be understood that various modifications in form, construction and arrangement of parts may be made within the spirit and scope of the following claims.

Having thus described my invention, what I claim as new, and desire to secure by Letters Patent, is:

1. A machine for cutting from a strip and assembling a series of marking tags provided with attaching means projecting from one face of the tag comprising means for feeding the tag strip, means for severing the tags successively therefrom supporting means to receive the tag and means operable in synchronism with the cutting means for so depositing the tags thereupon as to insure continuous superimposed relation of the tags with the attaching devices of each tag lying back of the edge of the tag next beneath it.

2. A machine for cutting from a strip and assembling a series of marking tags provided with attaching means projecting from one face of the tag comprising means for feeding the tag strip, means for severing the tags successively therefrom, supporting means to receive the tags, means for causing relative movement between the tag being delivered and the tag-receiving means operable progressively to superimpose the tags, with the attaching devices of each superimposed tag lying back of the edge of the tag next beneath it.

3. A machine for cutting from a strip and assembling a series of marking tags provided with attaching means projecting from one face of the tag comprising means for feeding the tag strip, means for severing the tags successively therefrom, a supporting chute to receive the tags, means operable to prevent flexure of the tag strip during the severance of the tags, means operable to deliver the severed tags successively to said chute in superimposed relation and to advance the successive tags to cause the attaching device of each superimposed tag to lie back of the edge of the tag next beneath it.

4. A machine for cutting from a strip and assembling a series of marking tags provided with attaching means projecting from one face of the tag comprising means for feeding the tag strip, means for severing the tags successively therefrom, a supporting chute to receive the tags, means operable to deliver the severed tags successively to said chute in superimposed relation and to advance the successive tags to cause the attaching device of each superimposed tag to engage the edge of the tag next beneath it and acting also progressively to advance the assembled tags along the chute.

5. A machine for cutting from a strip and assembling a series of marking tags provided with attaching means projecting from one face of the tag comprising means for feeding the tag strip, means for severing the tags

- successively therefrom, a supporting chute to receive the tags, means for adjusting the width of the chute to accommodate tags of different width, means operable to deliver 5 the severed tags successively to the chute in superimposed relation and to advance the successive tags to cause the attaching devices of each superimposed tag to lie beyond the edge of the tag next beneath it. 65
- 10 6. A machine for cutting from a strip and assembling a series of marking tags provided with attaching means projecting from one face of the tag comprising means for feeding the tag strip, means for severing the tags 15 successively therefrom, a supporting chute to receive the severed tags and an intermittently actuating pusher operable to engage an edge of the dropping tag and move the same in a direction lengthwise of said chute 20 and thereby cause the attaching device of each superimposed tag to engage the edge of the tag next beneath it. 70
7. A machine for cutting from a strip and assembling a series of marking tags 25 provided with attaching means projecting from one face of the tag comprising means for feeding the tag strip, means for severing the tags successively therefrom, a chute to receive the severed tags, means for preventing flexure of the tag strip during the severance of the tags whereby the tags will drop successively into the chute in superimposed relation, a rotatable pusher having arms to engage the successively deposited 30 tags and means for rotating said pusher intermittently to cause the tags to be progressively advanced in superimposed relation 35 along said chute. 75
8. A machine for successively cutting 40 marking tags, provided with attaching devices, from a strip and assembling said tags in superimposed relation, comprising a guide for the strip, means located at the end of said guide for cutting the tags from said strip, a chute to receive the severed tags and means for so depositing the tags in said chute as to insure superimposed relation of the tags with the attaching means of each tag lying back of the edge of the tag next beneath it. 80
- 50 9. A machine for successively cutting marking tags, provided with attaching devices, from a strip and assembling said tags in superimposed relation comprising a guide for the strip, a cutter located at the 55 end of said guide, a chute to receive the dropping severed tags in continuous superimposed relation, a rotatable pusher having arms to engage the dropping tags, pawl and ratchet mechanism operable by the reciprocation of said cutter to rotate said pusher 95
- 60 intermittently and thereby to force the attaching member of each superimposed tag against the edge of the tag next beneath it and also progressively to advance the superimposed tags along the chute. 100
10. A machine for successively cutting marking tags, provided with attaching devices, from a strip and assembling said tags in superimposed relation, comprising a guide for the strip, a reciprocating cutter located at the end of said guide, a chute formed of longitudinally extending flanged sections spaced apart to provide a way for said attaching devices, means for adjusting one of said sections relatively to the other to accommodate tags of different widths and means for progressively moving the tags longitudinally of the chute to cause the attaching device of each tag to lie beyond the edge of the tag next beneath it. 105
11. A machine for successively cutting marking tags, provided with attaching devices, from a strip and assembling said tags in superimposed relation, comprising a guide for the strip, a cutter located at the end of 110 said guide, a chute to receive the dropping severed tags in continuous superimposed relation, a rotatable pusher having backwardly curved arms to engage the dropping tags, pawl and ratchet mechanism operable by the reciprocation of said cutter to rotate said pusher intermittently and thereby to force the attaching member of each superimposed tag against the edge of the tag next beneath it and also progressively to advance the superimposed tags along the chute. 115
12. A machine for cutting marking tags from a strip and assembling said tags, comprising a guide for the strip, a stationary cutter located at the end of said guide above the path of the strip, a co-operating vertically reciprocating lower cutter and a yieldable stripper having a face normally positioned substantially in the plane of the edge of the stationary cutter, but movable by said reciprocating cutter during the operation. 120
13. A machine for cutting marking tags from a strip and assembling said tags comprising a support and guide for the strip, a stationary cutter located above the path of the strip, a co-operating vertically reciprocating lower cutter located intermediate of the stationary cutter and the support for the strip and means to receive the tags dropping from said cutters in continuous superimposed relation. 125

In testimony whereof, I have signed my name to this specification.

FREDERICK W. LAENCHER.
